UNITED STATES PATENT OFFICE.

RAY H. MANSON, OF ELYRIA, OHIO, ASSIGNOR TO THE DEAN ELECTRIC COMPANY, OF ELYRIA, OHIO, A CORPORATION OF OHIO.

TELEPHONE SWITCH-HOOK.

No. 841,993.

Specification of Letters Patent.

Patented Jan. 22, 1907.

Application filed December 2, 1905. Serial No. 290,039.

To all whom it may concern:

Be it known that I, RAY H. MANSON, a citizen of the United States, residing at Elyria, in the county of Lorain and State of Ohio, have invented a certain new and useful Improvement in Telephone Switch-Hooks, of which the following is a specification, reference being had therein to the accompanying drawings.

10 My invention relates to electrical switches of the type used in telephones; and it especially relates to the switch-lever used in connection therewith.

The object of the invention is to provide a 15 ever which will be neat in appearance, of sufficient structural strength to stand the wear and tear of ordinary use, and may be manufactured at a relatively low cost.

A further object of the invention is to provide a 20 switch-lever by stamping it from a single sheet of metal and then folding it so that its body and legs are of double thickness and in the desired shape.

The particular type of switch used in connection with my device forms no part of my 25 invention; but I have illustrated and will describe a switch similar to that shown in my application, Serial No. 200,899, filed March 31, 1904, and allowed September 30, 1905.

30 Specifically stated, my invention comprises a lever formed from a sheet of metal which is first stamped out so as to form a relatively long shank and a pair of legs having clover-shaped ends and then folded along a 35 central line, so as to double the thickness of the metal and form a substantially rigid construction throughout.

Subsidiary objects of the invention will appear as the following specific description is 40 read in connection with the accompanying drawings, which form a part of this application, in which—

Figure 1 is a side view of the switch-supporting frame with the lever mounted thereon. Fig. 2 is a bottom plan view of the lever. Fig. 3 is a side elevation thereof. Fig. 4 is a detail of one of the legs. Fig. 5 is a sectional view on line X X of Fig. 4; and Fig. 6 is a plan view, on a reduced scale, of the blank as it is 45 stamped out preparatory to folding.

Referring to the drawings, 1 represents a metal frame or support which is attached to the wall-set casing of any suitable material

and not shown, as it forms no part of my invention. This frame 1 is provided with a 55 horizontal flange or table 2, upon which the switch-springs 3 are mounted, and at its outer end with a pivot-post 4, forming a pivotal point for the stub-lever 5 and for the main hook-lever 6. The stub-lever 5 is provided with two transversely-projecting tongues 7 and 8, the former of which is slotted to receive the insulated end of the operating-spring 3^a of the set. The tongue 8 is made to engage a notch formed by ears 9 and 10, the latter of which is provided with a cam-face 11, which depresses the tongue 8 and the forward end of the lever 5 when the main hook-lever is pushed in place. An actuating-spring 12 is secured to the top of the table 2 and extends around underneath and engages a notch 20, formed in the lower side of the stub-lever and forward of the pivot-post 4, so as to normally force the tongue 8 into engagement with and to raise the main lever 6. All the 65 above is described and claimed in my application mentioned before and forms no part of this invention.

In Fig. 6 I have shown the main switch-lever 6 as it is stamped from the sheet metal preparatory to folding. It comprises a relatively long shank 13, having at one end thereof a notched ear 14, which is preferably disposed to the right of the median line y. At the opposite end of the shank the body is 80 bifurcated to form separate legs 15 and 16, both of which have their ends broadened out to substantially clover shapes, each leaf being punched out to form apertures 17 for the reception of suitable annular rivets 18. On 85 the right side of the median line y, at the edge and near the middle of the shank 13, are two ears or lugs 9 and 10, which form a notch 20, which is engaged when in operation by the tongue 8 of the stub-lever 5. One or both, 90 but usually only one, of the ears 9 and 10 is provided with a cam 11, previously described. The blank is now taken and by suitable pressure is folded along the lines y z, so as to double the thickness substantially throughout the entire length of the shank and the legs and so that the apertures of each clover-shaped end coincide. The rivets 18 are now inserted in the aperture 17 of each leg 15 and 16 and by any suitable means are upset to clamp the 95 two folds of the legs together. The device is

now ready to be polished and plated, after which it has the appearance of a finished cast switch-hook.

It will be clearly understood that I could use rivets or other suitable connecting means for the folds of the legs; but I desire to use the hollow rivets or thimbles 18, because it gives the lever a more finished appearance.

I am aware that other hook-levers have been made from one piece of metal formed into shape; but I am not aware that any attempt has been made to double down the metal so as to form a double thickness for the shank and the hook-prongs, as in my construction, which greatly strengthens the hook at the point where the two legs part from the lever proper. This is the weak part of a two-piece punched hook, and in a one-piece folded-over hook the prongs are of single thickness of metal and are weak from the lever out to the ends of the prongs.

Many changes might be resorted to without departing from my invention, and I consider all such changes well within the scope of the appended claims.

Having thus described my invention, what I claim, and desire to secure by Letters Patent, is—

1. A telephone switch-hook stamped from a single integral sheet of metal and having prongs and a shank, said prongs and shank being folded along their length to make the device of double thickness, and a pivotal connection at the end.
2. A telephone switch-hook constructed from a single integral sheet-metal blank bent and folded into shape to provide a shank or body and a hook or supporting prong of double thickness, and a pivotal connection of single thickness at the end of the shank.
3. A telephone switch-hook constructed from a blank having a main body portion adapted to be folded longitudinally and having end portions also folded longitudinally, said end portions being spread apart to form the prongs of the completed switch-hook, together with a rear portion extending longitudinally from the main body portion and constituting a pivotal connection.
4. As an article of manufacture, a sheet-metal blank adapted to be converted into a telephone switch-hook, said blank having a body portion and legs adapted to be folded longitudinally, said legs being spread apart and curved suitably to provide the completed switch-hook with prongs, together with a portion extending longitudinally to the rear of

said body, and notched to form a pivotal connection for the completed switch-hook.

5. A telephone switch-hook formed from one sheet of metal having a body portion and separated legs constituting prongs, said body portion and said prongs being folded throughout their length to double thickness, a pivotal connection at one end of the shank, and a bracing portion at the junction of the prongs with the body.

6. A telephone switch-hook formed from one sheet of metal and comprising a body portion and separated legs constituting prongs, said body portion and said prongs being folded throughout their length to double thickness, a notched pivotal portion extending to the rear of said body portion, and projecting ears on the shank forming an operating connection.

7. A telephone switch-hook formed from one sheet of metal and comprising a body portion and separated legs constituting prongs, said body portion and said prongs being folded throughout their length to double thickness, a notched pivotal portion extending to the rear of said body portion, and projecting ears defining a notch which forms an operating connection, one of said ears having a cam-face.

8. A telephone switch-hook formed from one sheet of metal and comprising a body portion and separated legs constituting prongs, said body portion and said prongs being folded throughout their length to double thickness, a notched pivotal portion extending to the rear of said body portion, projecting ears on the shank forming an operating connection, and a brace formed in folding the hook at the junction of the prongs with the shank.

9. A telephone switch-hook stamped from an integral sheet of metal and comprising a shank and prongs, said shank and prongs being folded throughout their entire length to double thickness, hollow rivets holding the ends of the prongs together, a pivotal connection of single thickness at the end of the shank, an operating connection comprising projecting ears intermediate the length of the shank, and a brace formed by folding the metal at the junction of the prongs with the shank.

In testimony whereof I have affixed my signature in presence of two witnesses.

RAY H. MANSON.
